DES. 2246

Sam'l H. Gibbs, of Albany, New York.

Assignee.

Abbott and Nible of Philadelphia, Penn.

Letters Patent No. 2246. Dated Jan'y 30. 1866.

Ante-dated Dec' 27. 1865.

Design for a Cook's portable Range.

The schedule referred to in these Letters Patent and making part of the same.

To all whom it may concern:

Be it known that I, Samuel H. Gibbs, of Albany, County of Albany, State of New York, have invented and reproduced a new and original design for a portable range, termed the Emerald, and I do hereby declare the accompanying Drawing with the following explanation of the same, to form a full, clear and exact description of the said Design.

The view in the accompanying drawing represents the Emerald Range, in perspective, A being the top plate, B, the front plate, C, one of the end plates and D, the bottom plate.

The top plate A, is edged with a plain moulding and has three openings for receiving cooking utensils.

The front plate B, has at the upper edge an ornamental moulding of the character shown in the drawing, and ornamental brackets D, at each vertical edge, there being at the lower edge, the plain moulding C. The joint plate has three end doors E, and a smaller door F, all edged with plain mouldings and having ornaments of the character illustrated.

On the front plate below the doors, is a protrusion G, ornamented substantially in the same manner as the doors.

The end plate C, is edged with a moulding similar to that on the front plate, and has three of the recesses for receiving said utensils.

2

DES. 2246

The bottom plate D is plain, and is edged with a plain moulding I claim. The ornamental figures and forms substantially as represented in and by the accompanying drawing, the whole forming a design for a portable range

In testimony whereof, I have signed my name to this specification in the presence of two subscribing witnesses
